UNITED STATES PATENT OFFICE.

OLIVER DAVID BABINEAU, OF MINNEAPOLIS, MINNESOTA.

INSULATOR.

Application filed December 7, 1925. Serial No. 73,576.

My invention relates to insulators for use in supporting electrical conductors and particularly to the type of insulator in which the conductor or wire is held from movement in a longitudinal direction. An object of the invention resides in providing a structure whereby the wire is firmly supported and is held from movement in either direction.

10 Another object of the invention resides in providing an insulator having a body portion forming an abutment having a depression therein for receiving a wire and in providing a member pivoted to said body portion 15 adapted to engage said wire and wedge the same against the wall of said depression on either side thereof so as to hold said wire from longitudinal movement in either direction.

20 A still further object resides in constructing said body portion and member so as to form a transverse groove along which a wire may lie, and in providing said member with a hump extending into the depression 25 in the body portion, said body portion having overhanging protrusions along said groove for holding said wire in place, and the hump on said member having a flange on which said wire rests for holding said 30 member in place and having a tip extending above said body portion for assisting in mounting the wire on the insulator.

With the foregoing and other objects in view, which will appear in the following 35 description, the invention resides in the novel combination and arrangement of parts and in the details of construction herein-after described and claimed.

In the drawing illustrating an embodiment of my invention:

Fig. 1 is a side elevational view of my improved insulator.

Fig. 2 is a plan view of the structure shown in Fig. 1.

45 Fig. 3 is a vertical sectional view taken on line 3-3 of Fig. 2.

Fig. 4 is a perspective view of the body portion of the insulator.

50 Fig. 5 is a perspective view of the wedge member of the insulator.

With the ordinary type of insulator used for supporting electrical conductors especially in transmission, telephone and telegraph lines considerable time is required in 55 stringing the wire and in attaching it to the insulators. In addition a substantial quan-

tity of tie wire is used for the purpose. When a wire is supported in the usual manner, and the same breaks, the wire slips along the insulators and sags for a number of 60 spans to either side of the break, thus causing additional labor in repairing and frequently producing shorts and cross-circuiting the lines. My invention overcomes these disadvantages as will become apparent.

65 In the drawings, I have shown an insulator constructed in accordance with my invention. The device consists of a body portion B which has mounted on it a member C adapted to operate in conjunction with 70 said body portion to support and hold from longitudinal movement a wire 10 as will be presently explained. The body portion B may be in the form of a frustum of a cone and is provided with a threaded socket 75 11 adapted to screw upon an ordinary insulator pin 12 as illustrated in Fig. 3. Around the lower portion of the body B is provided a skirt 13 which encloses the socket 11 protecting the threaded portion of the pin 12 80 from the weather and at the same time increasing the efficiency of the insulator.

85 At the top of the body portion B is a segmental shaped head 14 which has a vertically disposed abutment 15 at right angles to a horizontally disposed surface 16 on said body portion, this structure forming a rabbet along the upper portion of the insulator. Upon the surface 16 and in said rabbet is positioned the member C which 90 is also segmentally shaped and conforms in configuration to the head 14. Member C is arranged with vertically disposed surfaces 17, which face the abutment 15 of head 14 and are spaced therefrom, forming there- 95 with a transverse groove 18 for the reception of the wire 10. The member C is attached to the body portion B by means of a trunnion 19 formed integrally therewith, which depends from said member and is 100 fitted in a socket 20 formed in the upper part of the body portion B. By this means, said member is pivotally attached to said body portion so that the same may engage the wire to clamp it in a manner presently to 105 be described.

The wire 10 is held in place as follows: Medially of the abutment 15 is formed an arcuate depression 21. Into this depression extends a curved hump or protuberance 22 110 which is formed integral with the member C, being spaced sufficiently from the wall

of said depression to permit the wire 10 to pass between said protuberance and wall. In this manner a jog is formed in the groove 18 which allows the wire 10 to be kinked 5 as indicated at 23.

The device operates as follows: The kinked portion 23 of the wire 10 engaging the protuberance 22, causes the member C to be swung on the trunnion 19 whenever the 10 said wire is moved longitudinally. As will be noted, the trunnion 19 is eccentrically positioned relative to the wall of the depression 21. This causes said hump to be moved towards either of the sides of the 15 wall of the depression 21, which in turn forces the wire 10 against said wall so as to wedge it in place and prevent the further movement thereof in either direction.

To prevent the wire from becoming accidentally disengaged from the groove 18, as otherwise might occur at a low pole, the head 14 is provided with two overhanging protrusions 24 and 25 which obstruct the upward movement of the wire. Opposite the 25 protrusions on the member C the corner of the same along the surface 17 is beveled as indicated at 26 so that the groove 18 may be of substantially the same width throughout its upward extent to permit the insertion 30 of wire 10 into it. After the wire has been strung the same is prevented from having any transverse movement through the agency of the hump 22 which engages the kinked portion 23 of said wire and causes 35 it to lie closely against the abutment 15. In this position any upward movement of said wire must necessarily be along said abutment and is hence obstructed by either of the protrusions 24 or 25.

40 In mounting the wire upon the insulator the same is first inserted beneath either of the protrusions 24 or 25 as the case might be and slid over the beveled edge 26 of member C and into the groove 18. The 45 same is next bent around an upwardly projecting tip 27 on the hump 22 and then back again beneath the other of the protrusions and into said slot 18. In this manner the kink 23 is formed in the wire 10 which becomes lodged between the hump 22 and the 50 wall of the depression 21, said hump serving to wedge the wire in the insulator and obstruct it from movement in either direction, as previously brought out.

55 The member C is held in place by means of the wire 10 which rests upon a flange 28 formed around the lower portion of the hump 22 and which fits within the depression 21 along the bottom of the groove 18. This 60 flange also prevents the wire from creeping under the corners of the member C.

In the use of my improved insulator tie wires are entirely eliminated. The line wire can be mounted quickly and effectively in 65 the insulator, thereby reducing the time re-

quired to string the same. After the line has been erected the same remains at all times taut and properly supported between poles and in the event that the wire breaks the line will not sag at adjacent spans. 70

Changes in the specific form of my invention, as herein disclosed, may be made within the scope of what is claimed without departing from the spirit of my invention. 75

I claim:

1. An insulator comprising a body portion having an abutment formed with a depression for receiving a wire, a member pivoted to said body portion having a hump extending into said depression to engage a wire therein, said hump extending above the body portion and providing a guide for the insertion of the wire between said body portion and said member, said member being movable to clamp said wire and hold it 80 from longitudinal movement in either direction. 85

2. An insulator comprising a body portion having a segmental shaped head, a supplemental head member pivoted to said body portion adjacent said segmental shaped head and spaced therefrom to form a transverse groove for the reception of a wire, said segmental shaped head having a depression therein, and said supplemental head member having a hump extending into said depression and engaging said wire, said groove inclined toward said member near the top thereof and extending parallel therewith below the upper portion thereof, said hump 100 projecting above said groove. 105

3. An insulator comprising a body having a part of the upper top thereof removed to leave a segmental shaped head and to form a rabbet opposite said head, a supplemental head member of segmental shape positioned in said rabbet adjacent said segmental shaped head and being spaced therefrom to form a transverse groove for the reception of a wire, said segmental shaped head having a depression therein, and said supplemental head member having a protuberance extending into said depression and engaging said wire, a socket formed in said body, and a trunnion formed on said supplemental head member fitted within said socket for pivoting said supplemental member on said body portion, said trunnion being disposed so as to throw said protuberance toward the wall of the depression at either side thereof upon movement of the supplemental head member and wedge said wire against said wall to hold the wire against movement in either direction. 110 115 120

4. An insulator comprising a body having a part of the top thereof removed to leave a segmental shaped head and to form a rabbet offsetting said head with a horizontal and a vertical surface, a supplemental head member of segmental shape positioned with 125 130

- in said rabbet adjacent said segmental shaped head having a horizontal and a vertical surface, said horizontal surfaces contacting and said vertical surfaces being spaced to form a transverse groove for the reception of a wire, said segmental shaped head having a depression in its vertical surface and said complemental head member having a protuberance on its vertical surface 10 extending into said depression and engaging said wire, a socket formed in said body in the horizontal surface of said rabbet, and a trunnion issuing outwardly from the horizontal surface of said complemental head member fitted within said socket for pivoting said complemental member on said body portion, said trunnion being disposed so as to throw said protuberance toward the wall of the depression at either side thereof upon movement of the complemental head member, and wedge said wire against the wall to hold the wire against movement in either direction.
5. An insulator comprising a body having a part of the top thereof removed to leave a segmental shaped head and to form a rabbet offsetting said head with a horizontal and a vertical surface, a complemental head member of segmental shape positioned within said rabbet adjacent said segmental shaped head having a horizontal and a vertical surface, said horizontal surfaces contacting and said vertical surfaces being spaced to form a transverse groove for the reception of a wire, said segmental shaped head having a curved depression in its vertical surface and said complemental head member having a protuberance on its vertical surface extending into said depression and engaging said wire, a socket formed in said body in the horizontal surface of said rabbet, and a trunnion issuing outwardly from the horizontal surface of said complemental head member fitted within said socket for pivoting said complemental member on said body portion, the center of curvature of said depression lying between the center of said trunnion and said protuberance, so as to cause said protuberance to move toward the wall of said depression at either side thereof upon movement of the complemental head member upon
- said trunnion as its axis, so as to wedge the wire against said wall and to hold the same from movement in either direction.
6. An insulator comprising a body adapted to support a wire, said body having an abutment formed with a vertical surface, a complemental member pivoted to said body and having a vertical surface substantially parallel with the vertical surface of said body, a depression formed in the center portion of the vertical surface of said body, a hump formed on the vertical surface of said member and extending into said depression, said hump extending above the upper surface of the insulator and being free above the surface thereof, and overhanging protrusions formed on the body of the insulator at the upper corners thereof along said vertical surface, said protrusions co-operating with the extended portion of said hump for guiding and holding a wire within said groove.
7. An insulator comprising a body adapted to support a wire, said body having an abutment formed with a vertical surface, a complemental member pivoted to said body and having a vertical surface substantially parallel with the vertical surface of said body, a depression formed in the center portion of the vertical surface of said body, a hump formed on the vertical surface of said member and extending into said depression, said hump extending above the upper surface of the insulator and being free above the surface thereof, and overhanging protrusions formed on the body of the insulator at the upper corners thereof along said vertical surface, said protrusions extending past said hump and toward the vertical surface of said member, said member having the upper corners along the vertical surface thereof removed to maintain said groove of substantially the same width throughout its extent, said protrusions co-operating with the extended portion of said hump to guide a wire into said groove and to hold the same therein.

In testimony whereof, I have signed my name to this specification.

OLIVER DAVID BABINEAU.
